UNITED STATES PATENT OFFICE.

THOMAS NATHAN RUSSELL, OF CHICAGO, ILLINOIS, ASSIGNOR TO CHICAGO-CLEVELAND CAR ROOFING COMPANY, OF CHICAGO, ILLINOIS, A CORPORATION OF ILLINOIS.

CAR-ROOF.

1,290,666.

Specification of Letters Patent.

Patented Jan. 7, 1919.

Application filed April 8, 1915. Serial No. 13,902.

To all whom it may concern:

Be it known that I, THOMAS NATHAN RUSSELL, a citizen of the United States, residing in Chicago, in the county of Cook and State 5 of Illinois, have invented a new and useful Improvement in Car-Roofs, of which the following is a specification.

The invention relates to outside car roofs, and has for its objects to improve the construction of the roof supporting frame, the carlines thereof, the roof sheets, and the means for supporting and securing the roof sheets in place on such frame; and for further objects to secure all of the advantages 10 in economy and strength of construction, and in repair of the roof, which are incident to my improved design.

With such objects in view the invention consists in the parts and combinations there- 20 of hereinafter set forth and claimed.

In order to make the invention more clearly understood I have shown in the accompanying drawings means for carrying the same into practical effect, without limiting my improvements, in their useful applications, to the particular construction which, for the purpose of example, has been delineated. In said drawings—

Figure 1 is a plan view of a portion of a 30 car roof embodying the invention, portions of the roof sheets and other parts being removed or broken away to better display the frame.

Fig. 2 is a side view of the same.

Fig. 3 is a vertical section transverse of 35 the car, on a larger scale, on line III—III of Fig. 1.

Fig. 4 is a longitudinal central, vertical section of a portion of the roof, taken at one 40 end of the car, on line IV—IV of Fig. 1.

Fig. 5 is a vertical sectional view of one of 45 the roof sheet securing combined bolts and rivets, on a larger scale and of approximately full size, before the same has been riveted.

Fig. 6 is a vertical section across one of 50 the carlines and the connected portions of two roof sheets, illustrating the means for securing the sheets to the carlines.

Fig. 7 is a similar view illustrating one 55 of said fastening devices in connection with and as a means for supporting the running board.

Figs. 8, 9 and 10 are respectively a plan

view, a side view and an end view of one 55 of the carlines.

Fig. 11 is a vertical central section of one 60 of the roof sheets, taken longitudinally of the car.

Fig. 12 is a plan view of the eaves portion 65 of the same.

Fig. 13 is a horizontal section on line XIII—XIII of Fig. 11.

In Figs. 11 to 13 middle portions of the 70 roof sheet are broken away.

Referring to the drawings, the upper part 75 of the car body frame, which is the supporting frame for the roof, comprises side plates which are of what is commonly known as a Z-bar cross section, comprising a vertical web 1, an inwardly extending top horizontal flange 2 and an outwardly extending bottom horizontal flange 3. These side plates are united at the ends of the car by end plates of any suitable character. I prefer to employ end plates of the form shown in Fig. 4, which are arched from side to side of the car and comprise an arched flange 4 extending inwardly from the end of the car and resting by suitable flat ends on the top flange 80 2 of the side plates. This end plate also comprises a vertical end web 5 arranged transverse of the car and having at its lower edge a horizontal flange 6 which is or may be united by brackets 7 with the end posts 85 8 of the car frame.

The side plates are supported between their ends by side posts or stakes 7 and braces 9, with which the bottom flange 3 is united by brackets 10 riveted to the said 90 plates (Figs. 2 and 3).

Side and end sheathing 11, 12 is or may be attached to the inner sides of the upright portions of the car frame, and extending up within the vertical webs 1 of the side plates 95 and the vertical webs 5 of the end plates (Figs. 3 and 4).

At suitable intervals along the side plates are arranged carlines which are arched from side to side of the car (Figs. 3, 8, 9 and 10). Each carline has in cross section the form of an inverted channel bar of U or trough-like shape (Figs. 6 and 7) having vertical webs 13 and connecting top web 14 and outwardly extending bottom side flanges 15. The ends of the carline are formed with horizontal flanges 16, which are continuations of the flanges 15, which are bent down

out of and below the arched line of the flanges 15 to form roof supporting seats, and which rest upon the horizontal flanges 2 of the side plates (Fig. 3), and at the extreme 5 ends of the carline it is formed with vertical depending end flanges 17 which are or may be continuations of all of the parts 13, 14 and 15 of the carline and which fit on the outside of the vertical webs 1 of the side 10 plates, the said flanges 17 being extended longitudinally of the car as indicated at 18 in Figs. 8 and 10. Along the upper edges of the extensions 18 are formed horizontal shoulders 18' (Fig. 4) which rest on the side 15 plates at each side of the carline. This widely extended angle, composed of vertical and horizontal faces at each end of the carline, in which the outer upper angles of the side plates are engaged, has a strong bracing 20 effect to keep the carline erect and truly transverse of the car, and enables a single bolt 21 to be used at each end to unite the carline with the side plate. This is a material labor-saving device in both assembling 25 and repairing. The carline is or may be die-formed of one integral piece of heavy sheet metal, being pressed into the permanent form shown. The flanges or seats 16 are perforated at 19 for riveting to the flanges 2 of the side plates, the end flanges are perforated at 20 to be secured, as by bolts 21, to the vertical webs of the side plates, and the top web 14 is perforated at 22 to receive the roof sheet fastening devices hereinafter 30 described.

The roof sheets are shown at 23, and are or may be die-formed of medium heavy sheet metal so as to have substantially the configuration shown. They are arched from 40 eaves to eaves of the roof, conforming substantially to the arches of the carlines. The main portions of the roof sheets rest on the bottom side flanges of the carlines (Fig. 6), and are formed with upward bends 24 extending 45 longitudinally of the car and to near the margins of the sheets and over the bottom side flanges of the carlines. The bodies of the roof sheets thus derive strong supporting rigidity directly from the carlines.

The sides of the roof sheet (transverse of the car) are formed with upwardly extending flanges 25, 25' and outwardly extending flanges 26, 26'. The said upwardly extending flanges are arranged at the outer sides 50 of the vertical webs 13 of the carlines, and the said outwardly extending flanges are arranged across the top webs of the carlines and lapped thereon, the flange 26' underlapping 55 within the overlapping flange 26. The latter is further formed at its edge with a depending flange 27 which incloses the flange 25' of the next sheet when the parts are all assembled (Fig. 6). One side flange 60 of the roof sheet, comprising the parts 25',

26' may be described as of L-shape; and the other side flange of the sheet, comprising the parts 25, 26 and 27 may be described as of U-shape. The extreme edge of the said L-shape flange is bent upward toward the 70 under side of the said U-shaped flange, as shown at 28, for purposes later described and to cut off any splashing and leakage which might occur if the flange 27 should be bent outward out of normal position. The 75 eaves portions of the roof sheets are bent down to form depending vertical eaves flanges 30 which fit against the outer sides of the vertical webs 1 of the side plates. The roof sheet side flanges flow into or terminate in the said flange 30 and fit over and envelop the outer ends of the carline and the end flanges thereof. The flange 30 is formed with outwardly extending recesses 31 which extend to each side of the carline, within 80 which fit the extended longitudinal end flanges 18. The flange 30 is perforated at 85 32 to correspond with the perforations 20 and receive the bolts 21. It is also formed with one or more intermediate perforations 90 33 (Fig. 13) through which it may be secured to the side plate by bolts 34. The flanges 26 and 26' are perforated as shown at 95 29, 29' to correspond with the perforations 29 of the top web of the carline. Through these perforations pass combined 100 bolts and rivets 36 (Figs. 5, 6, 7). These devices comprise a fixed shoulder 37 which rests on the top web 14 of the carline and is inclosed by a large perforation 29' of the 105 flange 26', a bolt shank 38 which passes down through a perforation 22, a washer 39 applied against the under surface of the web 14, a nut 40 which clamps the bolt in place, and a rivet portion 41 above the 110 shoulder 37 which rivet portion passes up through a perforation 29 and is riveted down upon the flange 26 to form a watertight joint. The shoulder 37 is preferably in the form of a flange integral with the 115 combined bolt and rivet and thicker than the flange 26'. The flanges 26 and 26' are thus held firmly, but separated so as to prevent any capillary action which might lead water between the flanges 26, 26' or to the 120 perforations 29', 22. When the parts are assembled the lip 28 enables the flange 26 to hold the flange 26' down in place, and conversely the lip aids in supporting the running board saddle.

The described construction of roof sheet fastening is or may be of general application where roof sheets are lapped on a car roof frame, and produces an outside watertight joint and also enables the parts to be 125 assembled or detached with great convenience.

The described functions of this fastening are preserved and it is also used for securing the running boards in place. It would 130

be impracticable to include the running boards within the rivet 41, and the fastening for the said boards is off-set from the sheet fastenings by a metal saddle 42 one edge of which is held under two or more of the rivets 41 and by which a water-tight joint is made with the flange 26. The saddle is extended on that side of the carline on which is located the lip 28, so that, while the saddle derives a solid main support from the carline through the medium of the rigid shoulder 37, the lip 28 aids in sustaining the saddle at a distance from the carline.

10 The running boards 47 rest on the saddles 42 and are secured to the outer parts of the same, beyond the carlines, by bolts 44.

15 The end sheets are formed with only one upwardly and outwardly extending side flange, and are formed at the other side with a depending flange 45 which is bent down over the end fascia 46 (Fig. 4.)

20 What is claimed is:

1. In a metal car roof, in combination: carlines of inverted U-shape in cross section, with flat top webs and outwardly extending bottom side flanges; and roof sheets formed at each side with an upwardly and outwardly extending side flange, the upwardly extending parts of the side flanges 25 being arranged at the outer sides of the vertical web of the carlines and the outwardly extending parts of both of the meeting sheets being lapped across the top webs of the carlines, and the main portions of the sheets 30 being extended over and carried on the bottom side flanges of the carlines, and means whereby the lapped parts of the roof sheets 35 are spaced apart over the carlines.

2. In a metal car roof, in combination: carlines of inverted U-shape in cross section, with flat top webs and outwardly extending bottom side flanges; roof sheets formed with upwardly and outwardly extending side flanges, the upwardly extending parts of the side flanges 40 being arranged at the outer sides of the vertical webs of the carlines and the outwardly extending parts being arranged across the top webs of the carlines, and the main portions of the sheets being extended 45 over and carried on the bottom side flanges of the carlines; and means whereby said outwardly extending side flange parts are spaced apart and secured to the top webs of the carlines; and fastening devices which 50 pass through the top webs of the carlines and through the outwardly extending parts of the side flanges of both roof sheets where they are lapped.

3. In a metal car roof, in combination: carlines of inverted U-shape in cross section, with outwardly extending bottom side flanges, and with vertical end flanges extended longitudinally of the car beyond 55 said bottom side flanges; and roof sheets formed with upwardly and outwardly ex-

tending side flanges, the upwardly extending parts of the side flanges being arranged at the outer sides of the vertical webs of the carlines and the outwardly extending parts being arranged across the top webs of the carlines, and the main portions of the sheets being extended over and carried on the bottom side flanges of the carlines; and means whereby the inner and outer lapped portions of the roof sheets are held separated and each secured water-tight to the carline.

4. In a metal car roof, in combination: arched carlines of inverted U-shape in cross section, with outwardly extending bottom arched side flanges, and with vertical end flanges which are extended longitudinally of the car beyond said bottom side flanges, and which are formed with horizontal seats consisting of portions of said bottom side flanges which are pressed down out of and below the line of the arch of the carline flanges and are adapted to rest on the side plates at each side of and beyond said bottom side flanges; and roof sheets formed with upwardly and outwardly extending side flanges, the upwardly extending parts of the side flanges being arranged at the outer sides of the vertical webs of the carlines, the outwardly extending parts being arranged across the top webs of the carlines, and the main portions of the sheets being extended over and carried on the bottom side flanges of the carlines.

5. In a metal car roof, in combination: carlines of inverted U-shape in cross section, with outwardly extending bottom side flanges, and with vertical end flanges which are formed by flattening out the U-shaped portion of the carlines and are extended longitudinally of the car beyond said bottom side flanges; and roof sheets formed with upwardly and outwardly extending side flanges, the upwardly extending parts of the side flanges being arranged at the outer sides of the vertical webs of the carlines, the outwardly extending parts being arranged across the top webs of the carlines, and the main portions of the sheets being extended over and carried on the bottom side flanges of the carlines; the roof sheets being formed with depending eaves flanges which envelop the vertical end flanges of the carlines and are adapted to be attached directly to the side plates, said eaves flanges being formed with outwardly extending recesses at each side of the carlines within which fit the extended longitudinal end flanges of the carlines.

6. In a metal car roof, in combination: carlines of inverted U-shape in cross section, with outwardly extending bottom side flanges, and with vertical end flanges which are formed by flattening out the U-shaped portion of the carlines and are extended longitudinally of the car beyond said bot-

1. **tom side flanges, and which are formed with horizontal shoulders which are adapted to rest on the side plates at each side of and beyond said bottom side flanges; and 5 roof sheets formed with upwardly and outwardly extending side flanges, the upwardly extending parts of the side flanges being arranged at the outer sides of the vertical webs of the carlines, the outwardly extending 10 parts being arranged across the top webs of the carlines, and the main portions of the sheets being extended over and carried on the bottom side flanges of the carlines; the roof sheets being formed with de- 15 pending eaves flanges which envelop the vertical end flanges of the carlines and are adapted to be attached directly to the side plates, said eaves flanges being formed with outwardly extending recesses at each side 20 of the carline within which fit the extended longitudinal end flanges of the carlines.**

2. **In a metal car roof, in combination: arched carlines of inverted U-shape in cross section with flat top webs and outwardly 25 extending bottom side flanges; roof sheets formed with upwardly and outwardly extending side flanges, one of the said flanges of a sheet being of L-shape and the other being of U-shape, the upwardly extending 30 parts of the side flanges being arranged at the outer sides of the said carlines and the outwardly extending parts being arranged across the tops of the carlines, the L-shaped flange of one sheet being inclosed by the 35 overlapping U-shaped flange of the next sheet, and the main portions of the roof sheets being supported by the said bottom side flanges of the carlines; means for spacing apart the said roof sheet flanges over 40 the carlines and fastening devices by which the outwardly extending parts of the sheet flanges are both secured to the top webs of the carlines, said fastening devices passing through said top webs to the interior in- 45 verted trough portions of the carlines.**

3. **In a metal car roof, in combination: a roof frame; roof sheets the side edges of which are lapped on each other; and fastening devices by which the lapped portions 50 of the sheets are secured to the said frame, said fastening devices being permanently secured to the overlapped portions to form water-tight joints, and removably secured to the under-lapped portions and to the said frame.**

4. **In a metal car roof, in combination: carlines; roof sheets the side edges of which are lapped on each other on the tops of the carlines; and fastening devices by which the 60 lapped portions of the sheets are secured to the carlines, said fastening devices being permanently secured to the overlapped portions to form water-tight joints, and passing through perforations in the under- 65 lapped portions and removably secured to**

the under-lapped portions and to the car- lines.

5. **In a metal car roof, in combination: inverted U-shaped carlines; roof sheets the side edges of which are lapped on each other 70 on the top webs of the carlines; and fastening devices by which the lapped portions of the sheets are secured to the carlines, said fastening devices having shoulders beneath the over-lapped seat portions and having 75 their upper ends riveted down on the same and being permanently secured to the overlapped portions to form water-tight joints, and removably secured to the under-lapped portions and to the carline.**

6. **In a metal car roof, in combination: carlines of inverted U-shape in cross section with outwardly extending bottom side flanges; roof sheets formed with upwardly and outwardly extending side flanges, the 85 upwardly extending parts of the side flanges being arranged at the outer sides of the vertical webs of the carlines and the outwardly extending parts being arranged across the top webs of the carlines, and the main portions of the sheets being extended over and carried on the bottom side flanges of the carlines; and fastening devices which pass through the top webs of the carlines and through the outwardly extending parts of 90 the side flanges of both roof sheets where they are lapped; the said fastening devices comprising combined bolts and rivets each having a fixed shoulder thereon which fits in an aperture in the under-lapping roof sheet 100 flange, the outer end of the fastening device being riveted on the overlapping roof sheet flange to form a water-tight joint, and the bolt end extending through the top web of the carline and removably secured at the 105 under side thereof.**

7. **In a metal car roof, in combination: arched carlines of inverted U-shape in cross section with flat top webs and outwardly 110 extending bottom side flanges; roof sheets formed with upwardly and outwardly extending side flanges, one of the said flanges of a sheet being of L-shape and the other being of U-shape, the upwardly extending**

115 parts of the side flanges being arranged at the outer sides of the said carlines and the outwardly extending parts being arranged across the top of the carlines, the L-shaped flange of one sheet being inclosed by the overlapping U-shaped flange of the next 120 sheet, and the main portion of the roof sheets being supported by the said bottom side flanges of the carlines; and fastening devices by which the outwardly extending parts of the sheet flanges are both secured to the top webs of the carlines, said fastening devices passing through said top webs to the interior inverted trough portions of the carlines; the 125 said fastening devices comprising combined bolts and rivets each having a fixed shoulder 130

- thereon which fits in an aperture in the under-lapping roof sheet flange, the outer end of the fastening device being riveted on the overlapping roof sheet flange to form a 5 watertight joint, and the bolt end extending through the top web of the carline and removably secured at the under side thereof.
13. In a metal car roof, in combination: carlines; roof sheets formed with upwardly 10 and outwardly extending side flanges, one of the said flanges of a sheet being of L-shape and the other being of U-shape, the upwardly extending parts of the side flanges being arranged at the sides of the said carlines and the outwardly extending parts being arranged across the tops of the carlines, the L-shaped flange of one sheet being inclosed by the U-shaped flange of the next sheet, and the extreme edge of the L-shaped 15 flange being bent upward toward the under side of the said U-shaped flange; and means for securing the side flanges of the roof sheets to the carlines.
14. In a metal car roof, in combination: carlines of inverted U-shape in cross section with outwardly extending bottom side flanges; roof sheets formed with upwardly 20 and outwardly extending side flanges, the outwardly extending flange of one sheet being lapped with the outwardly extending flange of the next sheet on the top web of the carline; and means for securing both of said outwardly extending lapped flanges to the 25 said top web; the main portions of the roof sheets being formed with upward bends extending longitudinally of the car and the ends of the said upward bends extending to near the margins of the sheets and over the bottom side flanges of the carlines.
15. A roofing sheet for metal car roofs,
- formed on an arch from eaves edge to eaves edge and with an arched carline-engaging flange at each side, one of said flanges being L-shaped and the other of said flanges being U-shaped and the top members of said 45 flanges being flat in directions transverse to the lines of the carlines.
16. In a car roof, as a means for securing lapped roof sheets to the carlines, and in combination with such sheets and carlines, 50 shouldered bolts having a water-tight engagement with the over-lapped sheet, and an independent engagement with the under-lapped sheet, and united with the carline below the shoulders of the bolts: 55
17. In a car roof, in combination: carlines of inverted U-form; and roof sheets formed with upstanding side flanges lapped over said carlines; the over-lapping flanges being of inverted U-form and the under-lapping flanges being of L-form with an upturned edge. 60
18. A car roof sheet formed with upstanding side flanges, one of said side flanges being of inverted U-form and the other of 65 said side flanges being of L-form with an upturned edge.
19. A pressed steel arched carline for car roofs, of inverted U-form with a flat top web and outstanding bottom side flanges, the 70 top web of the carline and said side flanges being united and bent down to form depending end flanges, and said side flanges being bent down out of and below the line of the arch to form horizontal seats next to said 75 end flanges.
